Primary Examiner — T Chase Nelson*Assistant Examiner* — Jamillah Khalil Abdullah(74) *Attorney, Agent, or Firm* — Merchant & Gould P.C.(57) **CLAIM**

The ornamental design for a footwear, as shown and described.

DESCRIPTION

FIG. 1 is a front, top and right side perspective view of a footwear according to the new design;

FIG. 2 is a front side elevation view thereof;

FIG. 3 is a back side elevation view thereof;

FIG. 4 is a right side elevation view thereof;

FIG. 5 is a left side elevation view thereof; and,

FIG. 6 is a top plan view thereof.

The bold broken lines represent stitching and are part of the claimed design. The non-bold broken lines in the drawings show portions that form no part of the claimed design.
